ARTHUR B. CUNNINGHAM, OF TOLEDO, OHIO.

GAS ANALYZING AND RECORDING APPARATUS.

1,311,952.

Specification of Letters Patent.

Patented Aug. 5, 1919.

Application filed April 8, 1919. Serial No. 288,446.

To all whom it may concern:

Be it known that I, ARTHUR B. CUNNINGHAM, a citizen of the United States, residing at Toledo, in the county of Lucas and State 5 of Ohio, have invented certain new and useful Improvements in Gas Analyzing and Recording Apparatus, of which the following is a specification.

This invention relates to mechanism for 10 determining the percentage of a gaseous constituent in a gas, such as carbon dioxid in products of combustion, and automatically recording the same and any variation thereof on a time operated chart, so that by 15 comparing the readings, the volume or amount of the particular constituent in the gas at different times may be ascertained.

The drawings illustrate a preferred embodiment of the invention. However, it is 20 to be understood that in adapting the same to meet different conditions, various changes in the form, proportion, and minor details of construction may be resorted to without departing from the nature of the invention 25 as claimed hereinafter.

Referring to the drawings, which illustrate the preferred embodiment of the invention,

Figure 1 is a diagrammatic view.

Fig. 2 is a top view of the tank and parts contained therein.

Fig. 3 is a sectional detail on the line 3—3 of Fig. 2, a portion of the fluid counter-balance of the recording mechanism being 35 broken away.

Fig. 4 is a horizontal section of the variable gas receiver or measuring chamber on the line 4—4 of Fig. 1.

Corresponding and like parts are referred to in the following description and indicated in the several views of the drawings by like reference characters.

The pipe leading from the source of gas supply such as a furnace is indicated by the 45 numeral 1. The water supplying pipe is designated by the numeral 2 and may connect with a water main or other source of water supply. The waste pipe for carrying off the spent water is indicated at 3, the tank 50 for containing certain parts is indicated at 4 and comprises a vertical portion of some considerable depth and a lateral portion

which is relatively shallow, indicated most clearly in Fig. 1. An opening 7 is provided in the lower portion of the tank and a pipe 55 12 leads therefrom and connects with the gas supply pipe 1 some distance above the tank 4. A branch pipe 1^b connects the pipe 1 with the pipe 2 at a point above the tank 4. A nozzle 5 is located in the pipe 2 about 60 in line with the branch 1^b. A valve 11 is located in the pipe 1 at a point between the connections of the pipes 12 and 1^b therewith. The water is supplied to the tank from the pipe 2 through a pipe 6 and as the level of 65 water rises in tank 4 it passes through opening 7 at bottom of tank into tubes leading out. The surface of water is never below 7 and this is always sealed from air. Jet 5 produces a partial vacuum at 9 and draws 70 in a quantity of gas at 1. When the water level in 4 is low, float 10 closes valve 11 causing the gas to pass by way of pipe 12 to point 8, thence through tube 8^a into and filling measuring chamber 13. The gas passes 75 out at bottom of measuring chamber through pipe 13^a, branch 1^a into pipe 1 and out through branch 1^b into the pipe 6. As the water rises in tank 4 it of course rises in the tube 12 leading out of 7 and when it 80 reaches point 8 it traps a certain volume of 85 gas in measuring chamber 13. The water also elevates float 10 opening valve 11 allowing the gas to pass directly through and out by the jet 5. As the water continues to rise it forces the gas out of measuring chamber 13 through the tubing 13^b at the top leading to the bottom of absorption tank 14. This tank is filled to about point 15 with a reagent to absorb the gas to be determined. 90 As the bubbles rise through the solution they strike baffle 16 causing them to travel more slowly and with a rolling motion. It is also necessary for it to travel a much greater distance through the solution giving ample 95 time for the solution to absorb all the gas subject to its action. As the gas enters 14 from tube 13^b it forces out a quantity of gas equal to that not absorbed by the reagent. This gas escapes through pipe 14^a and enters 100 measuring chamber 17 which is an inverted cup working on stem 18 in guide 19. The cup 17 works in receptacle 20 which is filled with water to drainage point 21, the water

forming a seal. In the meantime the water has risen in tank 4 so as to seal the lower end of a pipe 22 which leads through the receptacle 20 and terminates near the top 5 thereof within the chamber 17. As cup 17 floats in the water in receptacle 20, it rises in proportion to the quantity of gas forced into it as residue from the original charge measured in chamber 13. As the cup 17 10 rises it carries stem 18 upward until it strikes arm 24, working on point 25, moving pen arm 24^a and pen carried thereby to position to make correct record at the proper moment on a time controlled chart A. This 15 time will be when the friction point 34 rises which will be explained later.

Point 25 is adjustable up or down and to right or left to calibrate. A bracket B is secured to a support C in such a manner as 20 to have a limited vertical movement and lateral adjustment. This bracket pivotally supports the parts 24—24^a which may consist of elements constituting a lever having the form of a bell crank. Suitable fastenings b and b' secure the bracket to the support C. As the water in 4 rises it carries 25 float 26 which is connected to siphon tubes 27 and 27^a. These tubes are united at the top and connected with the waste pipe 3 by 30 means of a flexible gum tubing 27^b. Note tube 22 is in no way connected with float 26 or any of the siphon apparatus. See Fig. 2 which shows more clearly the tank 4 and contained parts looking down from the 35 top.

The float 26 and tubes 27 and 27^a are held in position by stem 28 and guides 29 and 30. Guides are very loose, especially 29 which gives stem 28 room to swing in circle 40 with the gum connection tubing 27^b as the float 26 rises. When the float 26 which is open at the top, strikes guide 29 it stops and as the water rises to the top of the float and flows therein the float 26 fills and 45 quickly sinks carrying with it the siphon tubes 27 and 27^a. The whole siphon system is now below the water and the water flows out at full stream at once.

Cup 31, has a hole 31^a in the bottom and 50 is suspended in tank from arm 32 by means of a chain 31^b or like connection. The top of this cup is lower than the water level when the water is at its highest point in the tank 4 it having filled through the hole 31^a 55 in the bottom of the cup. Semi-circle 35 attached to arms 24 and 24^a constitutes a rider for a shoe 34 at the outer end of the lever 32. A weight 36 on the outer end of lever 32 holds 34 in contact with 35, retaining 60 pen in position until the proper moment for recording. As the level of the water in tank 4 rapidly lowers, it recedes faster in the tank than the hole 31^a will let it out of the vessel 31 and the weight of water in

the vessel 31 overbalancing the weight 36 65 raises 34 allowing 24 to adjust its position to the highest point of stem 18. At this time 17 and 18 are at their highest point and the weight of 24 readily adjusts itself to rest on point of stem 18. Immediately 70 the water runs out of 31 through the hole 31^a in the bottom thereof and the weight of 36 brings friction surface 34 to bear on 35 holding pen in position until a new charge is ready for recording; 37 is a common siphon removing all water from float 26 as soon as the water in tank 4 has lowered its surface below the bottom of 26. When the water in tank 4 lowers below the end of tube 22 it relieves the residue gas in the 80 measuring chamber 17. As the gas passes out, 17 lowers to its original position ready for the next charge of gas.

When the water in tank 4 reaches the lower end of siphon tube 27 it admits air 85 and immediately the flow of water stops.

It has now completed the cycle and is ready for a new charge of gas.

No claim is made for recording means, chart, clockwork for operating chart, or 90 chemical compound for use in 14 to absorb gas. I may use reagents in general use, or reagents may be prepared for special requirements. This apparatus may be used for continuous analysis and recording of any 95 single gas in a compound providing the proper reagent is used to absorb the gas in 14. It is especially designed for recording the percentage of carbon dioxid in gases of combustion. The two tubes 27 and 27^a, 100 and the rising and falling feature are the principal working parts. All previous siphons work nicely when they have exactly the proper amount of water supplied. If not enough they will drain over and the 105 siphon will not flow. If too much is supplied the siphon will not stop as it should but will continue to carry off the water as supplied. With this arrangement no water can drain off, no matter how small the supply, until the siphon tubes connected to 26 sink. Then the siphon starts flowing at full velocity. When the water level reaches the lower end of tube 27 the tube admits air and the flow of water stops immediately. By 115 this method the system is enabled to operate regardless of the flow of water. It is of course evident that if the flow of water is slow the cycles of operation will not be completed as quickly as when the supply is more 120 abundant, but the principal point is that the cycles will be complete.

The arrangement of valve 11 gives a continuous supply of gas fresh from the source. It is not necessary that valve 11 125 should close tightly as it is only a deflector when the gas should be diverted through measuring chamber 13. Point 8 is slightly

below the bottom of measuring chamber 13. The tubes leading upward from point 8 to chamber 13, and downward from 13, are very small the volume of gas measured is 5 always uniform, therefore 17 will always be raised to a corresponding height less the volume of gas absorbed in 14. The water supply in almost every instance is cold. I have placed a coil 2^a of the water supply 10 tube 2 in the water seal in 20 to keep it cool and condense any moisture that might be carried from 14. Some of the moisture will be condensed in the tube leading from 14 through the cold water of 20 and run back 15 in the solution of 20. Any moisture that escapes through this tube will be condensed on the surface of the cold water of 20 keeping the water at constant level of drainage point 21. It will be necessary to only occasionally add water to 14. It is not necessary 20 that either 14 or 20 maintain a constant level, but is better that both be kept to the proper level. It is observed that the gas in the final measuring chamber 17 is the same 25 temperature that it was in the first measuring chamber 13, this being essential to avoid any variation in volume of gas. He makes no claim to cooling the gas. I use the coil 2^a for a two-fold purpose, to condense any 30 moisture in the gas thereby maintaining a constant level in 20, and to maintain a constant temperature for final measurement. The baffle 16 in 14 increases by three times 35 the distance the gas must travel through the reagent. It also gives the bubbles a rolling motion exposing them more to the action of the reagent. This permits the use, with good results, of reagents until completely exhausted.

40 The foregoing description and the drawings have reference to what may be considered the preferred, or approved form of my invention. It is to be understood that I may make such changes in construction 45 and arrangement and combination of parts, materials, dimensions, et cetera, as may prove expedient and fall within the scope of the appended claims.

Having thus fully described my invention, what I claim as new and desire to secure by Letters Patent is:—

1. In apparatus of the character specified, a tank, a pipe for supplying water to the tank, a gas supplying pipe having connection with the water pipe and with the lower portion of the tank, a float controlled valve in the gas pipe actuated by the change of level of the water in the tank, a gas measuring chamber having connection with the gas 55 supplying pipe both above and below the valve therein, a separator having connection with the gas measuring chamber, a variable gas receiver having connection with the separator, a recording mechanism includ-

ing a lever, means for controlling the movements of the lever by the variable gas receiver and a fluid controlled receptacle in the tank and adapted to control the movements of the said lever. 65

2. In apparatus of the character specified, 70 a recording mechanism including a lever, a tank comprising a relatively deep and a relatively shallow portion, a vessel disposed in the deep portion of the tank and opened at its top, a siphon coacting with such vessel 75 for relieving the same of water whereby the vessel may be caused to rise and fall, a pipe extending into the deep portion of the tank, a waste pipe leading from the shallow portion of the tank, a flexible tubing connecting the two pipes, a vessel disposed in the tank and having a relatively small opening in its bottom, a recording mechanism including a lever which has the said vessel connected thereto, means for supplying water 80 and gas, a float controlled valve in the gas supplying pipe, a measuring chamber connected with the pipe containing the float controlled valve, a separator having connection with the measuring chamber and a variable gas receiver having connection with the separator and adapted to control the movements of the said lever in conjunction with the fluid controlled vessel. 85

3. In apparatus of the character specified, 90 a tank comprising relatively deep and shallow portions, means for supplying water to the tank, a waste pipe leading from the shallow portion of the tank, two tubes disposed in the deep portion of the tank and terminating in the lower portion thereof at different elevations, a flexible tubing connecting the waste pipe with the upper ends of the tubes, a receptacle disposed in the deep portion of the tank and open at its top, a siphon 100 in connection with said receptacle and a vessel disposed in the upper portion of the tank and having a relatively small opening in its bottom, said vessel being adapted to control a recording mechanism. 105

4. A gas analyzing and recording apparatus, comprising a recording mechanism including a lever and a variably supported marking arm, a tank comprising relatively deep and shallow portions, means for supplying water and gas to the tank, a float controlled valve in the gas supplying pipe, an open top vessel arranged in the tank, a siphon in conjunction therewith, tubes disposed in the deep portion of the tank, a waste pipe leading from the shallow portion of the tank, a flexible tubing connecting the waste pipe with the upper ends of the said tubes, a gas measuring chamber having connection with the part of the gas pipe containing the float controlled valve, a separator for receiving the gas from the measuring chamber, a variable gas receiver in con-

connection with the separator, a pipe connecting the upper portion of the receiver with the lower portion of the tank to be sealed by the water therein, means utilizing the movement of the gas receiver for controlling the said lever and a vessel open at the top and having a relatively small opening in its bottom disposed in the upper portion of the

tank and having connection with the said lever.

In testimony whereof I affix my signature in presence of two witnesses.
